UNITED STATES PATENT OFFICE.

CARL LINDENTHAL, OF NEW YORK, N. Y.

DESIGN FOR GIMP.

SPECIFICATION forming part of Design No. 22,267, dated March 7, 1893.

Application filed February 6, 1893. Serial No. 461,269. Term of patent 7 years.

To all whom it may concern:

Be it known that I, CARL LINDENTHAL, a citizen of the United States, and a resident of the city of New York, in the county and State 5 of New York, have invented and produced a new and original Design for a Gimp for a term of seven years, of which the following is a specification.

My invention relates to a design for a gimp, 10 which consists of a central band formed of raised pearl cord, sunken cords alongside said center-band, and edge-cords formed of approximately V-shaped portions separated by transverse cords.

15 The nature of my design is shown in the accompanying drawing to which reference is made.

a is the center-band of my gimp which is

made of raised cords that form a so-called pearl cord effect. Alongside of the raised center band are arranged longitudinal sunken cords *b b*, while the edges are formed of cords that are bound transversely by the cords *d*, so as to form approximately V-shaped figures *g*.

Having thus described my invention, I 25 claim as new and desire to secure by Letters Patent—

The design for a gimp, hereinbefore shown and described.

In testimony that I claim the foregoing as 30 my invention I have signed my name in presence of two subscribing witnesses.

CARL LINDENTHAL.

Witnesses:

H. WILLARD GRIFFITHS,
CHARLES SCHROEDER.
